UNITED STATES PATENT OFFICE.

DAVID P. CLEVELAND, OF DALLAS, TEXAS, ASSIGNOR OF ONE-HALF TO J. A. BERGFELD,
OF DALLAS, TEXAS.

ELEVATING RACK.

Application filed May 8, 1922. Serial No. 559,259.

To all whom it may concern:

Be it known that I, DAVID P. CLEVELAND, a citizen of the United States, residing at Dallas, in the county of Dallas and State of Texas, have invented certain new and useful Improvements in Elevating Racks, of which the following is a specification.

This invention relates to new and useful improvements in elevating racks.

10 The invention contemplates means for elevating automobiles and motor vehicles so as to afford ready access to the running gear and underside of the same, without having to drive the vehicle up an inclined support such as the commonly used stationary rack.

A particular object of the invention is to provide a rack which is normally substantially flush with the floor and has elevating means arranged below the floor, whereby a vehicle may be driven into position over the rack so as to be engaged and raised when said elevating means is operated.

A particular advantage of the invention resides in means whereby the vehicles may be elevated to various heights, thus enabling the operator to regulate the elevation in accordance with the work to be performed.

In carrying out the invention I provide a rectangular frame mounted on a plurality of hydraulic elevators which are arranged below the floor together with a plurality of liquid containing cylinders communicating with said elevators, and means for applying a fluid under pressure to displace the liquid in said cylinders, whereby the said elevators are actuated and the frame raised. The frame is provided with means for engaging the running gear and supporting the vehicle when elevated.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is a plan view of a rack constructed in accordance with my invention, the same having portions broken away,

Fig. 2 is an elevation of one side, the

lower portion of the hydraulic elevators not being shown,

Fig. 3 is an enlarged end view partly in section, showing the position of a motor vehicle over the rack, and

Fig. 4 is an enlarged longitudinal sectional view of one of the cylinders.

In the drawings the numeral 10 designates the end beams of a rectangular frame and 11, the longitudinal beams thereof. The said frame is carried by a plurality of hydrostatic elevators located below the floor 12, and is adapted to be received in a corresponding recess 13 in said floor so as to be normally flush therewith.

Each side of the frame is supported by a pair of said elevators which are spaced inwardly of the ends thereof. As will be seen in Fig. 3, a cylindrical core 14 is concentrically disposed within a vertical sleeve 15 of each elevator, the same being of such relative diameters as to provide a space 16 therebetween. The sleeve receives an annular screw threaded boss 14' on the lower end 78 of the core and is thereby held in position. An annular base flange 17 is located below the boss and is secured to a suitable footing 18, whereby the elevator is anchored in position. The upper end of the core is circumferentially grooved to receive a plurality of piston rings 19. A tubular plunger 20 snugly receives the core 14 in telescopic relation, and is slidable vertically thereon without engaging the sleeve 15. Normally, 80 the lower end of the plunger rests on the boss 14', while the upper end is provided with a cap 21. The plunger extends above the core 14, so as to provide a space 20' between the top of the latter and the cap 21. As will be 85 best seen in Figs. 2 and 3, the longitudinal beams 11 are suitably secured to the caps 21 of the plungers.

Mounted on the outer side of each beam 11, is a pair of cylinders 22 in opposed relation, each having communication at its outer end with the adjacent plunger by means of a connection 23 entering the cap 21 thereof. The inner ends of each pair of cylinders have connection with a T 24 which 100 is connected with one of the branches of a fluid pressure line 25 extending along the in-

ner sides of the beams 11 and across one of the end beams 10. Connected in the middle of said line at the said end beam is an angular extension 26 having a control valve 27 disposed therein. A flexible conductor such as a hose 28 engages over the end of said extension and has connection with a suitable source of fluid which is under pressure. I preferably employ air in said line to exert

10 the necessary pressure to operate the rack, but it is to be understood that the invention contemplates the use of steam and any other suitable fluid for this purpose.

The cylinders 22 and connections 23, contain 15 a liquid for transmitting the pressure exerted by said fluid to the plungers 20 in order to force the same upwardly. I preferably use oil or equivalent liquid for this purpose, because of its cushioning qualities; 20 however, any other suitable liquid may be used. As is shown in Fig. 4, a piston head 29 is slidable within each cylinder and is normally disposed at the inner end thereof.

Spaced inwardly of each end of the frame 25 is a pair of angular brackets 30, which are hinged to the inner top edges of the beams 11. As is shown in Fig. 3, said brackets terminate short of the running gear of the vehicle, and are adapted to engage the front 30 and rear axles of the same when the frame is slightly elevated. The pair of brackets engaging the rear axle may have suitable recesses or notches 31 in their upper ends in which to receive said axle and hold the same 35 against displacement. It will be seen that when the frame is lowered the brackets may be swung down upon the floor so as to be out of the way when moving a vehicle into position or removing the same. It is evident, 40 however, that various means may be provided to co-operate with the frame for engaging and supporting a vehicle in elevated position.

In operation it is pointed out that the vehicle 45 is driven into position on the floor 12 so as to straddle the frame of the rack. The brackets are then swung to an upright position as is shown in Figs. 2 and 3. By opening the valve 27 air or other fluid under pressure is conducted equally thru both branches of the line 25 and directed against the inner faces of the piston heads 29. It will be seen that such pressure causes said heads to displace the liquid in the cylinders 22, whereby 50 the same is conducted to the spaces 20' thru the connections 23. The pressure is thus transmitted to the plungers 20 by the liquid which, as it enters the spaces 20', forces said plungers upwardly. It is pointed out that 55 the said frame is mounted on the caps 21 and is raised with said plungers, causing the brackets 30 to engage the axles of the vehicle and elevate the same with said frame. The brackets provide a suitable support for

the vehicle when elevated and permit of free access to the underside parts thereof.

It will be seen that by a corresponding branch fluid pressure line with a single control valve located centrally, pressure is equally distributed at all times to the several elevators, thus a smooth, even movement is had and the rack maintained on a level during operation.

Various changes in the size and shape of the different parts, as well as modifications 75 may be made without departing from the spirit of the invention.

What I claim, is:

1. In an elevating rack, a frame member, a plurality of hydraulic elevators arranged 80 below the floor and carrying said member, liquid containers carried by the frame member and having communication with said elevators, and means for applying pressure against the liquid in said containers for displacing the same, whereby said pressure is transmitted to said elevators to actuate the same.

2. In an elevating rack, a frame member, a plurality of hydraulic elevators arranged below the floor and carrying said member, pairs of oppositely disposed cylinders carried by the frame member, each communicating with one of said elevators and having a piston head slidable therein, said cylinders being adapted to contain a liquid, and common means for applying pressure against the piston heads of all cylinders simultaneously, whereby the liquid in said cylinders is displaced and the said elevators are actuated.

3. In an elevating rack, a horizontal frame having means for engaging the running gear of a vehicle, hydraulic elevators disposed under and carrying said frame, means for 105 delivering a liquid to said elevators for operating the same, and a fluid pressure means for displacing said liquid.

4. In an elevating rack, a horizontal frame having means for engaging the running gear 110 of a vehicle, hydraulic elevators disposed under and carrying said frame, means for delivering a liquid to said elevators for operating the same, a fluid pressure means for displacing said liquid, and a single means for 115 controlling the fluid pressure means.

5. In an elevating rack, a horizontal frame having means for engaging the running gear of a vehicle, hydraulic elevators disposed under and carrying said frame, pairs of oppositely disposed cylinders carried by the frame, each having communication at its outer end with the adjacent elevator, said cylinders adapted to contain a liquid, and a common fluid pressure line one branch of which is connected with each pair of cylinders.

6. In an elevating rack, a horizontal

frame having means for engaging the running gear of a vehicle, hydraulic elevators disposed under and carrying said frame, pairs of oppositely disposed cylinders carried by the frame, each having communication at its outer end with the adjacent elevator, said cylinders adapted to contain a

liquid, a common fluid pressure line one branch of which is connected with each pair of cylinders, and a single control means connected in said line. 10

In testimony whereof I affix my signature.

DAVID P. CLEVELAND.
